DISPENSING TRAY FOR PLASTIC BAGS AND THE LIKE

Kenneth A. Smith, 2416 SE. 9th Ave.,
Portland, Oreg. 97214

Filed Feb. 24, 1969, Ser. No. 15,884

Term of patent 14 years

Int. Cl. D9—99

U.S. Cl. D52—2

FIG. 1

FIG. 2

FIG. 3

FIG. 4

FIG. 5

FIG. 6

FIG. 1 is a plan view of a dispensing tray for plastic bags and the like, showing my new design.

FIG. 2 is a front elevation as viewed from the bottom in FIG. 1.

FIG. 3 is a rear elevation as viewed from the top in FIG. 1.

FIG. 4 is a side elevation as viewed from the left in FIG. 1.

FIGS. 5 and 6 are front and side perspective views, respectively, of the dispensing tray shown in the preceding views.

I claim:

The ornamental design for a dispensing tray for plastic bags and the like, as shown.
